VICTOR ERICKSON

BY
Victor J. Evans
ATTORNEY

UNITED STATES PATENT OFFICE.

VICTOR ERICKSON, OF SAN FRANCISCO, CALIFORNIA.

OIL CAN.

Application filed January 31, 1925. Serial No. 6,085.

To all whom it may concern:

Be it known that I, VICTOR ERICKSON, a citizen of the United States, residing at San Francisco, in the county of San Francisco and State of California, have invented new and useful Improvements in Oil Cans, of which the following is a specification.

This invention relates to improvements in oil cans.

10 The principal object of this invention is to produce an oil can which with a slight pressure will force the oil from the end of the spout.

15 Another object is to produce a device of this character which is extremely simple and therefore cheap to manufacture.

Another object is to provide means for protecting the spout when not in use.

20 A further object is to provide means to prevent leakage when the can is not being used.

Other objects and advantages will be apparent during the course of the following description.

25 In the accompanying drawings forming a part of this specification, and in which like numerals are employed to designate like parts throughout the same,

Figure I is a vertical cross section of my 30 device, and

Figure II is a vertical cross section showing the manner of reversing the spout when not in use.

It is common practise to discharge oil 35 from an oil can by pressing upon the bottom of the can which is usually curved so as to provide for this pressure. This, however, is not sufficient in many instances to express a sufficient quantity of oil and is 40 further hard to manipulate.

I have therefore provided a can which has a piston located with the same, which piston forces the oil out of the can, in accordance with the pressure exerted upon the same.

45 In the accompanying drawings wherein for the purpose of illustration is shown a preferred embodiment of my invention, the numeral 5 designates a can having a filling opening closed by a plug 6. Slidably mounted within said can is a piston preferably formed of leather and having down-turned edges as shown at 7. This piston is confined between the metal discs 8 and 9 which are held together by screws 11 and 50 12. The piston thus constructed is secured

to a tube 13, which tube extends through a packing gland 14 secured upon the cover 16 of the can.

A spring 17 is secured to the bottom of the can and contacts the under surface of the 60 disc 9. An opening 18 forms a connection between the tube 13 and the interior of the can at a point below the piston. This tube 13 has secured to its upper end an enlarged portion 19 to which is secured finger pieces 65 21 and 22.

The interior of this enlarged portion 19 is screw-threaded so as to receive the screw threaded portion 23 of the spout 24. Mounted within the spout is a partition 26 having 70 a port formed therein, which port is normally closed by a valve 27 held against the partition by a spring 28. The result of this structure is that when the can is filled with oil some of the oil will pass into the 75 chamber below the piston and when the piston is forced down, this oil will be expressed through the tube 13, pass the valve 27 and out of the spout 24.

As soon as the operator releases the pressure upon the finger pieces 21 and 22, the spring 17 will move the piston upwardly, leaving a partial vacuum beneath the piston, which action will draw more oil from the portion above the piston to a point beneath 85 the piston ready to be discharged as soon as the piston is again moved downwardly.

By viewing Figure II it will be noted that the spout may be removed from the position shown in Figure I and reversed so as to be 90 normally protected within the tube 13. At the same time this places the valve 27 in such a position that any attempt to expel the oil will merely cause the valve 27 to seat more firmly, thus preventing any discharge when 95 the spout is in this position.

It will accordingly be seen that I have provided an oil can which is simple and highly efficient in use.

It is to be understood that the form of 100 my invention, herewith shown and described is to be taken as a preferred example of the same, and that various changes in the shape, size and arrangement of parts may be resorted to without departing from the spirit 105 of the invention or the scope of the subjoined claim.

Having thus described my invention, I claim:—

110 In a device of the character described,

a can, a piston mounted in said can, means for normally maintaining said piston out of contact with the bottom of said can, a tubular member secured to said piston, a port formed in said piston and connecting with said tubular member, an enlarged portion formed on said tubular member at a point outside of said can, finger pieces secured to said enlarged portion, a spout removably secured to said enlarged portion, said spout having an enlarged end adapted to fit within the said enlarged portion in such a man-

ner that said spout may project outwardly therefrom or may be reversed so as to be telescoped within said tubular member, and a valve positioned in said spout and adapted to open in such a manner as to discharge the contents of the can through said spout when said spout is projecting outwardly from said tubular member. 15

20 In testimony whereof I affix my signature.

VICTOR ERICKSON.
